UNITED STATES PATENT OFFICE.

EDWIN F. TRAPP, OF VALLEY STREAM, NEW YORK, ASSIGNOR TO WESTERN ELECTRIC COMPANY, INCORPORATED, OF NEW YORK, N. Y., A CORPORATION OF NEW YORK.

SIGNALING SYSTEM.

Application filed December 2, 1920. Serial No. 427,791.

To all whom it may concern:

Be it known that I, EDWIN F. TRAPP, a citizen of the United States of America, residing at Valley Stream, in the county of 5 Nassau, State of New York, have invented certain new and useful Improvements in Signaling Systems, of which the following is a full, clear, concise, and exact description.

This invention relates to improvements in 10 signaling systems, and more particularly, to a signaling system which is adapted to apply varying potential to a subscriber's telephone line upon which the receiver has inadvertently or otherwise been left off its 15 switchhook. This potential causes the receiver to produce a tone designed to attract the attention of the subscriber to the fact that he should replace his receiver.

Heretofore, it has been proposed to employ 20 so-called howler systems adapted to apply a potential of varying magnitude to a subscriber's line when the subscriber has inadvertently left his receiver off the switchhook and to provide for the automatic disconnection of the varying potential immediately 25 following the restoration of the subscriber's receiver to its switchhook. The aforesaid systems have, however, in so far as the applicant is aware made no provision for dis- 30 continuing the application of the varying potential after a predetermined interval, or for apprising the operator at the trouble desk if at the end of such interval the subscriber does not respond to the howling tone. 35 This latter feature is desirable in that the steady production of a howling tone at the subscriber's substation for an indefinite period would be objectionable to the subscriber and further, if the varying potential 40 is automatically continued for only an interval sufficient to attract the subscriber's attention if he is within hearing distance of his instrument and is then discontinued, the operator is relieved from supervising the connection and may direct her attention to other 45 duties.

It is one of the objects of the invention to provide means for connecting the source of varying potential to a subscriber's line whenever the receiver is inadvertently left off its 50 switchhook and for disconnecting the source after a definite interval.

It is a further object of the invention to provide an automatic switching mechanism 55 for connecting the source of varying poten-

tial to a subscriber's line for a definite interval and to provide means for disconnecting the source whenever the subscriber replaces his receiver on the switchhook.

A further object of the invention is to provide supervising means for supervising the application of the varying potential and a still further object of the invention is to provide operator controlled means for repeatedly applying the source of varying potential to the subscriber's line. 60 65

A further object of the invention is to provide trunking means for extending a connection from a subscriber's line to a trouble operator's position. 70

It is believed that a clearer understanding of the invention may be had from the following description taken in connection with the accompanying drawings in which—Fig. 1 shows the line of a calling subscriber terminating at an automatic exchange in a line switch, a diagrammatical representation of a district selector switch and office sender at the exchange and a jack ended trunk circuit extending to the trouble desk; Fig. 2 shows 75 the circuits of an operator's cord and associated howler apparatus at the trouble desk for connection with the trunk circuit of Fig. 1; and Fig. 3 shows the cord circuit of a monitoring operator at the trouble desk for 80 initially connecting with the subscriber's lines which appear to be in trouble. 85

For a disclosure of the complete organization of circuits, Fig. 2 should be placed beneath Fig. 1 and Fig. 3 beneath Fig. 2. 90

The invention has been illustrated in connection with an exchange system operating upon a full mechanical basis. A subscriber's line L has been illustrated terminating in an individual line switch 100 which has access 95 to the district selector switch 150. The subscriber's line is equipped with the well-known substation apparatus, and since the line terminates in an automatic exchange it is also equipped with the usual impulse dial 100 S. The district selector switch 150 has access in the well-known manner to other selector switches (not shown) for extending connections to desired subscribers' lines and to special traffic trunk circuits. In Fig. 1 a 105 traffic trunk circuit 175 has been illustrated for extending a connection to the trouble operator's desk of the exchange. For controlling the setting of the district selector switch and such other switches as may be employed 110

in the establishment of desired connections, an office register sender mechanism 125, the registers of which are adapted to be set through the operation of the subscriber's impulse dial S, is diagrammatically represented by the apparatus enclosed within the dotted lines in Fig. 1. Since the sender mechanism 125, line switch 100 and district selector switch 150 form no essential part of the invention, but enter only incidently into the disclosure thereof, only such portions of their circuits have been illustrated as is considered necessary to an understanding of this invention. For a complete disclosure 15 of this apparatus and a full description of the manner in which it functions, reference may be had to the application of O. H. Kopp, Serial No. 465,294, filed April 28, 1921.

Associated with the office sender mechanism 125 is a link circuit terminating in a jack J at the sender monitoring position on the trouble desk. In case the calling subscriber removes his receiver from its switch-hook and then fails to extend a connection, a permanent signal is displayed before the monitoring operator and the operator then connects a cord circuit such as shown in Fig. 3 with the link circuit for the purpose of challenging the subscriber. The cord circuit of Fig. 3 is not only equipped for establishing such connections with calling lines which appear to be in trouble, but is also arranged for monitoring on connections which have been established to called lines which are in trouble. The central office portion of such lines, pending the clearing of the trouble, are connected at the main distributing frame to plugging-up tie lines extending to the operator's position and terminating in jacks such as illustrated at J', and the outside portion of such lines are disconnected.

In view of the fact that the connection incoming to the called line and jack J' may be established through automatic switching mechanism, the cord circuit of Fig. 3 is provided with mechanism for tripping machine ringing without charging a call against the calling subscriber, and also with a flashing key for recalling an originating operator in the event that the connection has been extended semi-automatically through such an operator's position. The cord circuit is also provided with coin collection and refund keys to enable the operator to supervise calls which have been initiated from coin box lines.

A further link circuit extends between the sender mechanism and the operator's position, Fig. 3, and terminates thereat in jack J² to enable the monitoring operator to control the sender to connect the line of a subscriber who does not respond to the operator's challenge, through the district selector switch 150 to the link circuit 175 extending

to the trouble desk. By thus routing trouble calls to the trouble desk through the district selector switch 150, the office sender mechanism may be disassociated from the connection thus established and made available for regular service, while the trouble operator is attempting to clear up the trouble.

For answering calls incoming over the trunk circuit 175, a cord circuit shown in Fig. 2 is provided. This cord circuit is provided with a key K, which when operated to its talking position connects the operator's telephone set shown in Fig. 3 to the cord circuit and when operated into its other position initiates the application of a source of varying potential to the strands of the cord circuit and thus to the calling line. For producing a varying potential a source of current B and interrupter I are provided which are connected in series with the primary winding of transformer T. The secondary of transformer T is connected by means of a plurality of taps with a plurality of contacts in one of the banks of the step-by-step switching mechanism W. The step-by-step mechanism W is of the well-known type and is provided with four banks of contacts and associated brushes, which brushes are adapted to be driven, when started, through two complete revolutions unless the driving circuit of the switch is interrupted by the response of the subscriber to the howling tone during the first revolution of the switch. A supervisory lamp is provided for apprising the operator of the condition of the circuits.

In view of the fact that the cord circuits shown in Figs. 2 and 3 may be associated in the same position of the trouble desk, a single operator's telephone set O. T. has been illustrated in Fig. 3 for connection with either cord circuit.

Having in mind the foregoing brief description of the apparatus employed in carrying forward the inventive idea, it is believed that a clearer understanding of the invention may be had from the following description of its mode of operation. It will be assumed that the calling subscriber on the line L initiates a call by removing his receiver from its switchhook and then neglects to operate the dial S. Upon the removal of the receiver from its switchhook, the individual line switch 100 is operated in the well-known manner to extend the subscriber's line to an idle district selector switch 150, which thereupon becomes associated with an idle office register sender mechanism 125 in a manner fully set forth in the aforesaid application.

Upon the association of the office sender 125 with the district selector switch 150, the sequence switch (not shown) of the district selector switch 150 is advanced in the well-known manner for extending a dialing circuit from the subscriber's line L to the wind-

ings of the stepping relay 101 of the office sender. This circuit may be traced from grounded battery through the left-hand winding of stepping relay 101, conductor 102, 5 the outer armature and back contact of relay 200, conductor 201, the lower right-hand contact of sequence switch cam 103, the lower wiper of line switch 100, thence over the subscriber's line, the upper wiper of 10 line switch 100, the lower contact of sequence switch cam 104, conductor 105, the inner armature and back contact of relay 200, conductor 202 and thence to ground through the right-hand winding of stepping 15 relay 101.

In the manner fully set forth in the aforesaid application, if following the energization of stepping relay 101, the calling subscriber fails to operate his calling dial S 20 for setting the registers of the sender, a permanent signal becomes displayed before the monitoring operator whose cord circuit is disclosed in Fig. 3. In response to this permanent signal, the monitoring operator inserts the plug P of her cord circuit in the jack J.

Upon the insertion of the plug P in the jack J, a circuit is established for the monitoring relay 200, which may be traced from 30 grounded battery through the windings of sleeve relays 300 and 301, the sleeve contacts of plug P and jack J, conductor 302 and thence to ground through the winding of relay 200. Relay 301 is marginally 35 wound and does not receive sufficient current over the circuit previously traced because of the high resistance of the winding 200 and, therefore, does not energize. Relays 200 and 300, however, energize. Upon 40 the energization of relay 200, the impulse circuit previously traced is opened at the armature contacts of relay 200 and conductors 105 and 201 are thereupon extended through the front contacts of the armatures 45 of relay 200 over conductors 203 and 204 respectively to the tip and ring contacts of the jack J and thence through the tip and ring contacts of plug P to the tip and ring strands of the monitoring operator's cord 50 circuit.

Relay 300, upon energizing, closes at its left-hand armature and front contact a circuit for the supervisory lamp 303, but this circuit is immediately opened at the left-hand armature and back contact of supervisory relay 304, since relay 304 now becomes energized over a circuit which may be traced from grounded battery, through its right-hand winding, the right-hand armature and back contact of relay 305, the lower left-hand winding of repeating coil 306, the intermediate armature and back contact of relay 307, the ring contact of plug P and thence over the circuit previously 60 traced through the calling subscriber's line 65

loop and returning to the tip contact of plug P to the upper armature and back contact of relay 307, the upper left-hand winding of repeating coil 306 and thence to ground at the left-hand armature and back contact of relay 305. The calling subscriber is thus provided with talking current through the winding of supervisory relay 304.

Following the insertion of plug P in jack J, the monitoring operator operates the talking key 308 for connecting her set O. T. with the strands of the cord circuit. The operation of the key closes contact 309 and thereby establishes a circuit for relay 310, 75 which circuit may be traced from grounded battery, through the left-hand winding of relay 310, conductor 311, the inner right-hand armature and back contact of relay 312, key contact 309 and thence to ground at 80 the armature and front contact of relay 304. It is to be noted in this connection that relay 310 and the remaining apparatus enclosed within the dotted lines of Fig. 3 are 85 common to all of the cord circuits of the monitoring operator's position. Relay 310 upon energizing establishes a circuit for relay 313, which circuit becomes effective as soon as the interrupter cam 314 advances to such a position as to close its contact 315. 90 The circuit of relay 313 may be traced from grounded battery, through the winding of relay 313, the right-hand armature and back contact of relay 316, the outer right-hand armature and front contact of relay 310, 95 interrupter contact 315 and thence to ground at the normally closed contacts of the armature of relay 317. A locking circuit is also established at this time through the right-hand winding of relay 310, the front contacts of both of its right-hand armatures, interrupter contact 315 and thence to ground at the armature contact of relay 317 to insure that relays 313 and 316 function 100 through a complete cycle of operations even if the operator releases the key 308 prior to the completion of such cycle.

Relay 313 upon energizing establishes a locking circuit for itself extending through the winding of relay 316, the armature and 115 front contact of relay 313 and thence to ground at the left-hand armature and front contact of relay 310, but relay 316 does not energize in this circuit since its winding is shunted by a direct connection to ground 120 through its right-hand armature and back contact, the outer right-hand armature and front contact of relay 310, interrupter contact 315 and thence to ground at the armature contact of relay 317. As soon, however, as interrupter cam 314 advances to such a position as to open contact 315, the shunt around the winding of relay 316 is opened 125 and relay 316 energizes. Upon its energization, the initial energizing circuit of relay 130

313 is opened at the back contact of its right-hand armature and a circuit is established for the slow-to-release relay 307, which may be traced from grounded battery through the winding of relay 307, the outer right-hand armature and front contact of sleeve relay 300, the outer right-hand armature and back contact of relay 312, conductor 318, the right-hand armature and front contact of relay 316, the outer right-hand armature and front contact of relay 310, interrupter contact 315 and thence to ground at the normally closed armature contact of relay 317. This circuit does not become effective until interrupter cam 314 again advances to such a position as to close the contacts 315.

Upon the energization of relay 307 a momentary bridge is established across the tip and ring contacts of the plug P and the tip and ring strands of the cord circuit are momentarily opened. This function of relay 307 is without effect at this time. At its lowermost armature and front contact, relay 307 establishes a circuit for relay 319, which may be traced from grounded battery through the winding of relay 319, the lowermost armature and front contact of relay 307 and thence to ground at the left-hand armature and front contact of relay 316. Relay 319 upon energizing in this circuit closes a locking circuit for itself extending through its right-hand armature and front contact, the normally closed break contacts of the inner left-hand armature of relay 312, the winding of relay 312 and thence to ground at the inner right-hand armature and front contact of sleeve relay 300. At its left-hand armature and front contact, relay 319 prepares a branch circuit from the winding of relay 307 to the armature of relay 317, but without effect at this time.

Relay 312 does not energize at once in the locking circuit previously traced through the winding of relay 319, since its winding is shunted by a connection to ground from the right-hand armature and front contact of relay 319, the lowermost armature and front contact of relay 307 and thence to ground at the left-hand armature and front contact of relay 316. This shunt around the winding of relay 312 is maintained until relay 307 deenergizes which occurs at a predetermined interval after the opening of the circuit of relay 307 at the contact 315 of interrupter cam 314. When the shunt is removed from around the winding of relay 312, relay 312 opens the previously traced locking circuit of relay 319 and closes a new locking circuit for relay 319 extending from ground at contact 329 of key 308, through the outer left hand armature and front contact of relay 312 to the winding of relay 319 and also closes a locking circuit for itself extending from

grounded battery through its inner left-hand armature and front contact, its winding and thence to ground at the inner right-hand armature and front contact of sleeve relay 300.

Relay 312 at its outer right-hand armature and back contact opens the circuit previously traced through the winding of relay 307, at its inner right-hand armature and back contact opens the starting circuit previously traced through the left-hand winding of relay 310 and at the front contact of its inner right-hand armature establishes a circuit for the operator's set connecting relay 320, which circuit may be traced from grounded battery through the winding of relay 320, the front contact and inner-right-hand armature of relay 312, contact 309 of key 308 and thence to ground at the armature and front contact of supervisory relay 304. Upon the opening of the circuit of relay 310, relay 310 deenergizes and at its left-hand armature and front contact opens the locking circuit of relays 313 and 316. The circuits of the common apparatus of the operator's position are now in normal condition having served their purpose of causing the energization of relay 320 and the consequence connection of the operator's telephone set to the strands of the cord circuit. The common apparatus is primarily intended for controlling the operation of relay 307 for tripping machine ringing, when the monitoring operator answers on a connection incoming on a plugging up line terminating in a jack J' as will be described hereinafter. Upon the energization of relay 320, the operator's telephone set O. T. becomes connected with the right-hand windings of the repeating coil 306 over the armatures and front contacts of relay 320 and the outermost contacts of the talking key 308.

The operator now challenges the calling subscriber in an endeavor to ascertain from the calling subscriber the reason for the failure to dial a number after having removed his receiver from its switchhook. If the operator receives no response from the calling subscriber, she assumes that the calling line is either in trouble, or that the calling subscriber has removed his receiver and inadvertently left it off its switchhook. The operator will thereupon remove the plug P of her cord circuit from the jack J and reinsert it in the jack J².

Removal of plug P from the jack J opens the circuit previously traced through relays 200 and 300 and these relays deenergize. The deenergization of relay 300 opens the locking circuit of relay 312, which thereupon deenergizes and opens the circuits of relays 320 and 319. Upon the insertion of the plug P in jack J², relays 301 and 300 energize, but their operation at this

time is without interest. A circuit is now established between the office sender 125 and the operator's cord circuit over conductors 106 and 107 and in the manner fully set forth in the application of O. K. Kopp, Serial No. 465,294, filed April 28, 1921, heretofore referred to. The circuits of the office sender are so adjusted as to cause the setting of the district selector switch 150 through its brush and group selection movements, upon the terminals of the special traffic trunk 175 extending to the trouble desk. The setting of the switch 150 by the sender mechanism 125 is accomplished in the well-known manner with the sender sequence switch (not shown) in positions 2 and 4.

As soon as the brushes of the district selector switch 150 have been set upon the terminals of traffic trunk 175, the sequence switch (not shown) associated with the district selector switch 150 advances into position 10 in the well-known manner. The fundamental circuit from the office sender mechanism 125 is now extended to the windings of trunk relay 108 and may be traced as follows: Grounded battery, the left-hand winding of relay 108, the normally closed contacts associated with the upper armature of cut-off relay 109, trunk conductor 110, bank terminal 111 and brush 112 of the district selector switch 150, the lower contact of sequence switch cam 113, conductor 114, the armature and back contact of the No. 0' counting relay 115, the sender sequence switch contact 116 (6), the windings of the sender stepping relay 117, conductor 118, the upper contact of sequence switch cam 119, brush 120 and terminal 121 of the district selector switch 150, trunk conductor 122, the normally closed contacts of the intermediate armature of cut-off relay 109 and thence to ground through the right-hand winding of trunk relay 108. Upon the establishment of this circuit, the office sender sequence switch is advanced out of positions 6 and into position 14 in the well-known manner and the sequence switch of the district selector switch 150 is advanced out of position 10 and into position 11. From position 11 the sequence switch of the district selector is advanced through successive talking selection positions under the control of the office sender mechanism 125, and since the district selector switch has been so set by the office sender as to extend a connection to an operator's position, the sequence switch of the district selector is arrested in position 14. As soon as the sequence switch of the district selector leaves position 10½, the impulsive leads 105 and 201 are disassociated from the office sender mechanism and the conductors 114 and 118 of the fundamental circuit are also disconnected. The circuits of the office sender

mechanism thereupon return to normal condition and may be employed for controlling the establishment of other connections.

With the sequence switch of the district selector 150 in position 14, a circuit is now established from grounded battery through the left-hand winding of trunk relay 108, the normally closed contacts of the upper armature of relay 109, trunk conductor 110, bank terminal 111 and brush 112 of the district selector switch, the upper contact of sequence switch cam 113, the winding of polarized relay 123, the lower contact of sequence switch cam 119, brush 120 and bank terminal 121 of the district selector switch, trunk conductor 122, the normally closed contacts of the intermediate armature of relay 109 and thence to ground through the right-hand winding of relay 108. Relays 108 and 123 energize in this circuit, but the energization of relay 123 is without effect at this time. Upon the energization of relay 108, a circuit is established for the auxiliary signal 124, which may be traced from grounded battery through the lamp 124, the left-hand armature and front contact of relay 108 and thence to ground through the outer left-hand armature and back contact of make busy relay 135. At its right-hand armature and front contact, relay 108 closes a circuit for the trunk lamp 126, which may be traced from grounded battery through the slow interrupter 127, the normally closed contacts of the outer right-hand armature of relay 135, the right-hand armature and front contact of relay 108 and thence to ground through the trunk lamp 126. Trunk lamp 126 is flashed slowly in this circuit until the operator at the trouble desk answers in on the connection.

The operator at the trouble desk noting the flashing of lamp 126 inserts the plug 205 of an idle howler cord circuit at her position in jack 128 of the trunk circuit with which the flashing lamp 126 is associated, and assuming that the operator is the same operator who initially monitored the connection, she will also withdraw the plug P of her monitoring cord circuit from the jack J², thus restoring the circuits of the monitoring cord circuit to normal condition.

Upon the insertion of plug 205 in the jack 128, a circuit is established extending from grounded battery, through sleeve relay 206, sleeve contact of plug 205 and jack 128 and thence to ground through the winding of relay 109. Both sleeve relay 206 and the cut-off relay 109 energize in this circuit. Relay 109 upon energizing disconnects the windings of trunk relay 108 from conductors 110 and 122 of the trunk circuit and connects the conductors 110 and 122 to the tip and ring contacts of the jack 128. Trunk relay 108 is now held energized in a local circuit which may be traced from

grounded battery through its left-hand winding and to ground through the make before break contacts of the upper armature of cut-off relay 109. At its lowermost armature and front contact, relay 109 establishes a circuit extending through the winding of make busy relay 135, whereupon relay 135 becomes energized disconnecting the trunk lamp 126 from the interrupter 127 10 at its right-hand armature and normal contact and connecting lamp 126 in a steady circuit, which may be traced from grounded battery through the outer right-hand armature and front contact of relay 135, 15 the right-hand armature and front contact of relay 108 and to ground through lamp 126.

Relay 135 upon energizing closes a locking circuit for itself extending through its 20 winding, contacts 129 associated with its inner left-hand armature and thence to ground through the disconnect key 130. The make busy relay 135 is thus held energized independently of the cut-off relay 109 25 until the attendant operator releases it by operating the disconnect key 130. Relay 135 is thus maintained energized to connect a busy ground potential to the multiples of test terminal 131 appearing in the banks 30 of all district selector switches having access to the trunk circuit 175 over a circuit extending to terminal 131 over conductor 132 and the front contact of the inner left-hand armature of relay 135. With make 35 busy relay 135 energized and trunk relay 108 energized, the circuit previously traced for the auxiliary signal 124 is opened at the outer left-hand armature and back contact of make busy relay 135 and a new circuit for the auxiliary signal 124 is prepared 40 at the outer left-hand armature and front contact of relay 135, which circuit does not become effective until after the release of relay 108. At its inner right-hand armature 45 and front contact, relay 135 prepares a circuit from the fast interrupter 133, but since trunk relay 108 is energized at this time, this circuit is not completed through the lamp 126. Should the operator withdraw 50 the plug 205 from the jack 128 following the application of the howler tone to the subscriber's line, the calling subscriber having responded to the tone, without opening the disconnect key 130, the circuit 55 through the fast interrupter 133 will become extended through the right-hand armature and back contact of relay 108 to ground through the trunk lamp 126 to flash the lamp 126 rapidly to signal the attendant operator that the key 130 should be opened 60 to release the make busy relay 135 and remove the busy potential from the multiples of terminal 131.

Upon the insertion of plug 205 in the 65 jack 128 and the energization of sleeve relay

206 in the circuit previously traced, a circuit is established for the supervisory lamp 207, which may be traced from ground through the resistance element 208, lamp 207, the armature and front contact of relay 206 and thence to battery and ground through the armature and back contact of supervisory relay 209. This circuit, however, is immediately opened at the armature and back contact of relay 209 since relay 209 immediately becomes energized in a circuit which may be traced from the non-grounded pole of battery, the upper right-hand winding of repeating coil 210, conductor 211, the ring contacts of plug 205 and jack 128, the intermediate armature and front contact of relay 109, trunk conductor 122, bank terminal 121 and brush 120 of the district selector switch, the lower contact of sequence switch cam 119, the winding of polarized relay 123, the upper contact of sequence switch cam 118, brush 112 and bank terminal 111 of the district selector switch, trunk conductor 110, the upper armature and front contact of relay 109, the tip contacts of jack 128 and plug 205, conductor 212, the winding of supervisory relay 209 and thence to ground through the lower right-hand winding of repeating coil 210. The current now flowing through the winding of polarized relay 123 at the district selector is in such a direction as to cause the effective energization of relay 123 and the advancement of the sequence switch of the district selector out of position 14 100 and into position 15, in which latter position a direct talking circuit is established between the subscriber's line and the cord circuit of the trouble operator. At the district selector switch, the talking circuit may 105 be traced through the upper left-hand contact of sequence switch cam 104 and the lower left-hand contact of sequence switch cam 103. The movement of the sequence switch of the district selector out of position 14, disconnects the left-hand windings of repeating coil 134 from the calling line and talking current which was up to this time supplied to the calling line through the left-hand windings of repeating coil 115 134 is now supplied through the right-hand windings of repeating coil 210 of the operator's cord circuit. The functioning of the circuits of the district selector as just described is fully set forth in the patent to F. 120 A. Stearn and F. J. Scudder, No. 1,895,977, issued November 1, 1921.

The trouble operator may now operate her key K to the left to connect her set O. T., disclosed in Fig. 3, to the strands of the 125 cord circuit and may again challenge the calling subscriber. If no response is received she then operates the key K to the right, whereupon a circuit is established for the relay 213, which may be traced from 130

- grounded battery, through the armature and front contact of supervisory relay 209, winding of relay 213 and thence to ground at the lowermost alternate contact 214 of key K. Relay 213 upon energizing establishes a circuit for lamp 207 extending from grounded battery through the interrupter 215, the outer left-hand armature and front contact of relay 213, the outer right-hand armature and back contact of relay 216, the armature and front contact of sleeve relay 206 and thence to ground through the lamp 207 and resistance element 208. The lamp 207 is flashed in this circuit until either the subscriber responds by hanging up his receiver, or until the step-by-step switch W makes two complete revolutions as will be presently described.
- At its right-hand armature and front contact, relay 213 establishes a circuit for the cut-in relay 217, which may be traced from grounded battery through the winding of relay 217, the right-hand armature and front contact of relay 213 and thence to ground through brush 238 of the switch W and the normal contact of the bank with which it is associated. Relay 217 upon energizing in this circuit closes a locking circuit for itself extending through its inner right-hand armature and front contact and thence to ground through contact 214 of key K, thus locking the relay 217 energized independently of the switch W. At its outer right-hand armature and front contact relay 217 prepares a circuit for the disconnect relay 218 which circuit will be described hereinafter. At its left-hand armature and front contact, relay 217 closes the primary circuit of transformer T. This circuit may be traced from the upper terminal of the primary winding of transformer T, through impedance coil 219, the source of current B, interrupter I, the left-hand armature and front contact of relay 217, the left-hand armature and back contact of relay 218 and thence to the lower terminal of the primary winding of transformer T. Through the operation of interrupter I, current is permitted to flow intermittently in the primary winding T, whereby an alternating current is produced in the secondary winding of transformer T. Upon the energization of relay 213, a starting circuit for starting the step-by-step switch W is closed, which may be traced from grounded battery, through the winding of stepping magnet 220, the armature and back contact of this magnet, conductors 221 and 222, the inner left-hand armature and front contact of relay 213, the left-hand armature and back contact of relay 216, brush 223 and the normal contact of the bank with which it is associated and thence to ground through the interrupter 224. Upon the closure of this circuit, magnet 220 advances the brushes of the switch W one step, whereupon the wipers are automatically advanced through a complete revolution by a new circuit for the stepping magnet 220, which may be traced through the winding of magnet 220, the off normal contacts of the bank associated with the brush 223, brush 223 and thence to ground through the interrupter 224.
- As the stepping magnet 220 advances the brushes of switch W over their respective banks, the brush 238 engages successive contacts of its bank and thereby connects different portions of the secondary winding of transformer T to the left-hand winding of repeating coil 210. This circuit through the secondary winding of transformer T may be traced from ground through the uppermost alternate contact of key K, the left-hand windings of repeating coil 210, alternate contacts 225 of key K, the secondary winding of transformer T, successive taps from the portions of the secondary winding, successive contacts of the bank associated with brush 238 and thence to ground through brush 238. The current flowing in this circuit which was induced from the primary winding of transformer T is thus repeated from the left-hand winding of repeating coil 210, through the right-hand winding of the repeating coil and thence over the circuit previously traced and through the receiver at the calling subscriber's substation and produces therein a howling tone which is divided into two complete cycles during a single movement of brush 238 over its bank or during a half revolution of the step-by-step switch W, each cycle beginning with a tone of minimum magnitude and increasing to one of maximum magnitude. The tone will always begin with a minimum magnitude, since the primary winding of transformer T is closed only upon the energization of relay 217 and relay 217 cannot be energized except when the brush 238 is resting on the normal contact of its bank, which contact immediately precedes the first contact connected to a point in the secondary winding of transformer T, corresponding to the minimum number of secondary turns, or a number of turns which insures the minimum transmission ratio between the windings of the transformer.
- Should the calling subscriber in response to the howling tone replace his receiver upon its switchhook before the completion of the first revolution of the switch W, relay 209 becomes deenergized opening the circuit of relay 213, thereby opening the previously traced flashing circuit of the lamp 207 and opening the circuit hereinafter to be described which otherwise would cause a second half revolution of the switch W. The deenergization of relay 209 upon the replace-

ment of the receiver at this time closes a circuit through the back contact of relay 209 for causing the lamp 207 to burn steadily. The operator is thus apprised of the 5 fact that the subscriber has immediately responded to the howling tone.

The deenergization of relay 213 upon the response of the subscriber establishes a circuit for the disconnect relay 218, which may 10 be traced from grounded battery through the winding of relay 218, the outer right-hand armature and front contact of relay 217, the right-hand armature and back contact of relay 213, the inner right-hand armature and front contact of relay 217 and thence to ground at contact 214 of key K. Relay 218 upon energizing immediately 15 opens the circuit traced through the primary winding of transformer T and thus stops 20 the transmission of the howling tone.

If the subscriber does not replace his receiver at this time, when the brushes of the switch W reach the last contact in their respective banks the following circuits are 25 established; from grounded battery through the winding of relay 226, the armature and back contact of relay 227, the last contact of the uppermost bank of switch W and thence to ground through brush 228. Relay 30 226 upon energizing establishes a locking circuit for itself extending through its winding, the winding of relay 227, the armature and front contact of relay 226 and thence to ground through contact 214 of key K. Relay 35 227 does not energize in this circuit however until the brush 228 leaves the last contact of its bank as its winding is shunted by the ground connected at brush 228. When relay 227 does become energized in 40 series with relay 226, a circuit is prepared for relay 216. A second circuit which was established when the brushes of switch W reached the last contacts of their respective banks may be traced from grounded battery, 45 through the winding of stepping magnet 220, the armature and back contact of magnet 220, conductor 221, the last contact of the bank with which brush 223 is associated, brush 223 and thence to ground through the 50 interrupter 224.

Under the influence of the stepping magnet 220, the brushes of switch W are advanced into normal position, when the circuit of magnet 220 is again established over 55 conductors 221 and 222, the inner left-hand armature and front contact of relay 213, the left-hand armature and back contact of relay 216, the normal contact with which brush 223 is now in engagement and thence to 60 ground through the interrupter 224. In the manner previously described, the switch W is now driven through a second half revolution and the variable potential is applied to the calling line through the windings of 65 repeating coil 210. If the calling subscriber

replaces his receiver upon the switchhook during the second half revolution of switch W, the circuits of the cord circuit function as previously described.

If the receiver is not replaced, however, 70 upon the completion of the second half revolution of switch W, a circuit is established for relay 216 as soon as the brush 228 reaches the last contact of its bank, which circuit may be traced from grounded battery through the winding of relay 216, the armature and front contact of relay 227, the last contact of the uppermost bank of switch W and thence to ground through brush 228. Relay 216 upon energizing in this circuit 75 closes a locking circuit for itself extending from its intermediate armature and front contact and thence to ground through contact 214 of key K, opens at its outer right-hand armature and back contact the flashing 80 circuit of lamp 207 and at its left-hand armature and back contact opens the circuit previously traced by means of which the switch W was initially moved out of its normal position. Switch W is thus prevented 85 from going through another cycle of operations when it reaches its normal position. When the brush 223 engages the last terminal of its bank, the previously traced circuit through the winding of magnet 220 is closed 90 for advancing the brushes of the switch into normal position. Following the opening of the flashing circuit of lamp 207, the lamp 207 remains dark, since at this time supervisory relay 209 is still energized over the 95 subscriber's line loop, and the operator noting that the lamp 207 is dark is apprised of the fact that the calling subscriber has not 100 responded to the howling tone.

If the operator does not desire to again 105 apply the variable potential to the subscriber's line, she then operates the key K into its intermediate position, in which position the secondary winding of the transformer T is disconnected from the left-hand winding of repeating coil 210 and the locking circuit previously traced for holding 110 relays 216, 217 and 218 energized is opened and these relays thereupon retract their 115 armatures. When the operator withdraws the plug 205 from the jack 128, the circuits previously traced through relays 206, 209 and 120 109 are opened and the circuits of the operator's cord are then completely restored to normal position.

Upon the deenergization of sleeve relay 109 of the trunk circuit 175, the windings of relay 108 are again connected to trunk conductors 110 and 122 of the trunk circuit, and since at this time relay 135 is energized, the 125 trunk lamp 126 glows steadily. As soon as the trouble is cleared on the subscriber's line, either by the subscriber hanging up his receiver or by the outside test man, relay 108 becomes deenergized and the previously 130

- traced circuit through interrupter 133 and lamp 126 is closed to flash the lamp 126 rapidly to inform the operator that the trouble has been cleared and that she should 5 release the connection by throwing key 130 thereby unlocking the make busy relay 135 as previously described.
- If the operator desires to reapply the variable potential to the subscriber's line following a complete cycle of operations of the switch W, she may do so by again operating the key K to the right when the circuits will function in the manner previously described. If the key K is operated to its intermediate 15 position at any time when the switch W is off normal, a circuit will be closed to insure the return of switch W to normal, which may be traced from grounded battery, through the winding of stepping magnet 220, its armature and back contact, the off normal contacts of the lowermost bank of the switch, brush 229, conductor 230, normal contacts 231 of key K and thence to ground. 20 As soon as switch W reaches normal position, this restoring circuit is opened at the brush 229.
- The monitoring operator as hereinbefore stated may employ the cord circuit shown in Fig. 3 for answering calls which have come 30 to her position over a plugging-up line 321 terminating in a jack J'. If a subscriber's line is in trouble, the office end of such line is joined to a plugging-up line 321 at the main distributing frame and if a call is 35 extended through a full mechanical exchange to such a line which is in trouble, ringing current from the incoming selector switch applied over the brushes of the final selector switch will operate the ring down relay 322, which will thereupon lock up through its inner left-hand armature and front contact, its left-hand winding and the normally closed contacts associated with jack J', and will establish a circuit for the lamp 323. The monitoring operator noting the illumination of lamp 323 inserts the plug P of her cord circuit in the jack J', whereupon the right-hand winding of relay 322 is disconnected from the tip and ring conductors 40 of the plugging-up line and the locking circuit of the relay 322 is opened at the contacts of the jack, and lamp 323 is thereby extinguished.
- A circuit is now established through the 45 sleeve relays 300 and 301 of the operator's cord circuit and since the sleeve contact of the jack J' is connected directly to ground, both relays 300 and 301 become energized. Relay 301 upon energizing establishes a circuit for relay 305 which disconnects ground from the tip strand of the cord circuit and battery from the ring strand of the cord circuit and connects battery with the tip strand of the cord circuit through the left-hand winding of relay 304, the left-hand 50 armature and front contact of relay 305, the upper left-hand winding of repeating coil 306 and thence to the tip strand of the cord circuit.
- In the manner previously described, the common apparatus associated with the cord circuit functions to cause a momentary energization of relay 307, which momentarily establishes a bridge across the tip and ring contacts of the plug P over a circuit which 55 may be traced from the tip of the plug through the upper armature and front contact of relay 307, conductor 324, the innermost normally closed contacts of flashing key 325, conductor 326, resistance element 327 and thence to the ring contact of the plug through the intermediate armature and front contact of relay 307. The momentary establishment of this bridge is sufficient to trip machine ringing in the incoming selector switch, but is not of sufficient duration to cause the charging of the call against the calling subscriber. In this respect, these 60 circuits function in substantially the manner described in the application of J. W. Gooderham, Serial No. 427,445 filed November 30, 1920. Following the tripping of machine ringing, the operator's telephone set relay 320 becomes energized to connect the operator's telephone set to the strands of the cord circuit. The operator may then communicate with the calling subscriber to inform him that the desired line is out of order, following which the operator releases the connection at her position by withdrawing the plug P from the jack J'. 65
- If the connection has been established to the operator's position semi-automatically through an originating operator's position and the monitoring operator desires to recall the originating operator, she may do so by depressing the flashing recall key 325. Upon the operation of key 325, contact 328 of the key is closed to establish a circuit for the slow-to-release relay 317. Since at this time relay 319 is held energized over a circuit extending through the outer left-hand armature and contact of relay 312 and contact 329 of the talking key 308, a circuit is now 70 established for relay 307 which may be traced from grounded battery, through the winding of relay 307, the left-hand armature and front contact of relay 319 thence to ground at the armature and front contact of relay 317. The operation of relay 307 opens the strands of the cord circuit and thereby causes the operation of the supervisory relay at the distant originating operator's position. During the energization of relay 307, relay 304 is maintained energized over a circuit extending through its left-hand winding, the left-hand armature and front contact of relay 305 and to ground through the right-hand contact of key 325. 75 A connection between the operator's tele-

phone set O. T. and the originating operator's position is maintained during the energization of relay 307 over conductors 324 and 326, contacts 330 and 331 of key 5 325 and conductors 332 and 333.

If the monitoring operator desires to collect or refund a coin deposited in the calling subscriber's coin box, she may do so by operating either the coin collection key 334 or the 10 refunding key 335 respectively. The operation of either of these keys closes a circuit for relay 307 which may be traced from grounded battery through the winding of relay 307 and thence to ground through the 15 left-hand contacts of key 334 or key 335. If the operator depresses the coin collection key 334 coin collection current is connected to the tip contact of plug P from the source 336 of collecting current through the winding of pilot relay 337, the right-hand contact of key 334, conductor 324, the upper armature and front contact of relay 307 and thence to the tip of the plug. In a similar 20 manner by the operation of key 335, current from the source 338 may be connected through the pilot relay 339 over the right-hand contact of key 335, conductor 324 and to the tip of plug P. Since these circuits 25 form no essential part of the present invention, no further detailed description of the 30 operation of the cord circuit of Fig. 3 will be given.

In the foregoing description, the invention 35 has been described as applicable to an exchange operating upon a full mechanical basis. It is obvious, however, that the howler cord circuit may as readily be employed for applying variable potential to a manual subscriber's line for producing a howling tone 40 in the receiver of a subscriber's substation which has been inadvertently left off the switchhook, and the invention is to be interpreted to cover either of the aforementioned 45 applications of the invention.

45 What is claimed is:

1. In a telephone exchange system, a subscriber's line, a trunk circuit, means under the control of said subscriber's line for extending a connection from said line, operator 50 controlled means operative if the calling subscriber removes his receiver from the switchhook and fails to cause the extension of such connection for extending a connection from said line to said trunk circuit, a source of varying potential, and means for connecting said source operatively with said subscriber's line.

2. In a telephone exchange system, a subscriber's line, a trunk circuit, means under 60 the control of said subscriber's line for extending a connection from said line, operator controlled means operative if the calling subscriber removes his receiver from the switchhook and fails to cause the extension 65 of such connection for extending a connec-

tion from said line to said trunk circuit, a cord circuit for connection to said trunk circuit, a source for varying potential associated with said cord circuit, and means for connecting said source operatively with said 70 line.

3. In a telephone exchange system, a subscriber's line, a trunk circuit, means under the control of said subscriber's line for extending a connection from said line, means 75 operative if the subscriber inadvertently removes his receiver from the switchhook and fails to cause the extension of such connection for extending a connection from said line to said trunk circuit, a lamp signal associated with said trunk circuit, means for flashing said lamp upon the seizure of said trunk circuit, a cord circuit for connection with said trunk circuit, a source of varying potential associated with said cord circuit, and means for connecting said source operatively 80 with said line.

4. In a telephone exchange system, a subscriber's line, a source of varying potential, means including an operator's cord circuit 90 for associating said source with said line for a predetermined interval, and means under the control of said line for disconnecting said source prior to the expiration of said interval.

5. In a telephone exchange system, a subscriber's line having associated therewith a substation set in its operated position, a source of varying potential adapted for connection to said line, means including an operator's cord circuit for operatively connecting said source with said line for a predetermined interval, and means under the control of said line for disconnecting said source prior to the expiration of said interval when said substation is restored to its 100 normal non-operated position.

6. In a telephone exchange system, a subscriber's line having a substation receiver and switchhook, a source of varying potential adapted for connection with said line, means for operatively connecting said source with said line for a predetermined interval if said receiver is inadvertently maintained off said switchhook, means operative upon the replacement of said receiver for disconnecting said source, means for producing a signal during the connection of said source, and means for discontinuing said signal if said receiver has not been replaced at the 115 expiration of said interval.

7. In a telephone exchange system, a subscriber's line having a substation receiver and switchhook, a cord circuit for connection therewith, a source of varying potential associated with said cord circuit, operator controlled means for causing the connection of said source with said cord circuit if said receiver is inadvertently maintained off said switchhook, means for disconnecting said 125 130

- source after a predetermined interval, means operative upon the replacement of said receiver for disconnecting said source, means for producing a signal before the operator 5 during the connection of said source, and means for discontinuing said signal if the receiver has not been replaced at the expiration of said interval.
8. In a telephone exchange system, a subscriber's line having a substation receiver and switchhook, a cord circuit for connection therewith, a source of varying potential associated with said cord circuit, a key for causing the connection of said source with 10 said cord circuit if said receiver is inadvertently maintained off said switchhook, means for disconnecting said source after a predetermined interval, means operative upon the replacement of said receiver for 15 disconnecting said source, means for producing a signal during the connection of said source, and means for discontinuing said signal if said receiver has not been replaced at the expiration of said interval.
- 20 9. In a telephone exchange system, a subscriber's line having a substation receiver and switchhook, a source of varying potential adapted for connection to said line, means for operatively connecting said source 25 with said line for a predetermined interval if said receiver is inadvertently maintained off said switchhook, means operative upon the expiration of said interval for maintaining the connection of said source for a 30 second predetermined interval if said receiver is then off the switchhook, means operative upon the expiration of said second interval for disconnecting said source and means operative upon the replacement of 35 said receiver for disconnecting said source.
- 40 10. In a telephone exchange system, a subscriber's line having a substation receiver and switchhook, a source of varying potential adapted for connection with said line, means for operatively connecting said source with said line for a predetermined interval if said receiver is inadvertently maintained off said switchhook, means operative upon the expiration of said interval for maintaining 45 the connection of said source for a second predetermined interval, means operative upon the replacement of said receiver for disconnecting said source, a signaling device, means for intermittently operating 50 said device during the connection of said source, means for operating said device steadily if the receiver is replaced during said first interval, and means for disconnecting said device if said receiver is not 55 restored at the expiration of said second interval.
- 60 11. In a telephone exchange system, a subscriber's line having a substation receiver and switchhook, a cord circuit for connection therewith, a source of varying potential as- 65 sociated with said cord circuit, a key for connecting said source with said cord circuit if said receiver is inadvertently maintained off said switchhook, means for maintaining the connection of said source for a 70 predetermined interval, means operative upon the replacement of said receiver for disconnecting said source, a signaling device, means for operating said signaling device during the connection of said source, means 75 for disconnecting said signaling device upon the expiration of said interval if said receiver has not been replaced, and means operative in response to said signaling device upon repeated operations of said key for repeatedly connecting said source to said line for a predetermined interval.
- 80 12. In a telephone exchange system, a subscriber's line having a substation receiver and switchhook, a source of varying potential adapted for connection with said line, a step-by-step switch for operatively connecting said source with said line during one operating cycle of said switch if said receiver is inadvertently maintained off said switchhook, means operative thereafter for advancing said switch through a second operating cycle for maintaining the connection of said source if said receiver is then off the switchhook, means operative thereafter for 85 arresting said switch to disconnect said source, and means operative upon the replacement of said receiver for disconnecting said source.
- 90 13. In a telephone exchange system, a subscriber's line, a trunk circuit extending to an operator's position, means for extending a connection from said line to said trunk circuit, a cord circuit at said operator's position for connection with said trunk circuit, 95 a signal for said trunk circuit, means operative upon the seizure of said trunk circuit for operating said signal, manually operable means for releasing said trunk circuit, and means operative upon disconnection of said cord circuit from said trunk circuit for operating said signal in a distinctive manner until said releasing means is operated.
- 100 14. In a telephone exchange system, a subscriber's line, a trunk circuit extending to an operator's position, automatic switching means for extending a connection from said line to said trunk circuit, a cord circuit at said operator's position for connection with said trunk circuit, a signal for said 105 trunk circuit, means operative upon the seizure of said trunk circuit for operating said signal, a key associated with said trunk circuit for releasing said switching means, and means operative upon disconnection of said cord circuit from said trunk circuit for operating said signal in a distinctive manner until said switching means is released by the operation of said key.
- 110 15. In a telephone exchange system, a sub- 115
- 120

scriber's line, a trunk circuit extending to an operator's position, automatic switching means for extending a connection from said line to said trunk circuit, a cord circuit at 5 said operator's position for connection with said trunk circuit, a signal lamp for said trunk circuit, means operative upon the seizure of said trunk circuit for flashing said lamp, means operative upon the connection 10 of said cord circuit with said trunk circuit for rendering said trunk circuit non-select-

able and for operating said lamp steadily, a key for rendering said trunk circuit selectable, and means operative upon disconnection of said cord circuit from said trunk 15 circuit for operating said lamp in a distinctive manner until said key is operated.

In witness whereof, I hereunto subscribe my name this 29th day of November, A. D. 1920.

EDWIN F. TRAPP.
